Dean, Fairbank, Osgood & Husch.
ATTORNEY

UNITED STATES PATENT OFFICE

FRANKLIN LAMB, OF NEW YORK, N. Y., ASSIGNOR TO CARD DISPLAY, INC., A CORPORATION OF NEW YORK

CARD DISPLAY

Application filed May 15, 1929. Serial No. 363,125.

The device of the present invention while capable of a wide range of embodiment was primarily designed as an improvement over the card display disclosed in my copending 5 application Serial No. 358,248 filed April 26, 1929.

It will be recalled that objects of the invention of the prior application were to provide a decorative self supporting display 10 frame for price cards of the character commonly used in large quantities on the counters of department stores or the like, and to provide a temporary cap piece self sustaining in applied position on the frame, and 15 adapted to bear decorative matter appropriate to the season, whereby the frames might be suitably dressed for seasonal events without the need for printing special signs for such occasions.

20 The device of the present invention not only fulfills all of the above objects, but is further concerned with the provisions of a decorative cap member of substantial construction and luxurious appearance which, 25 when applied to the frame, will appear to be an integral part thereof. The cap piece is preferably itself in the nature of a supplemental frame for a supplemental card member which may display indicia appropriate to a particular store wide or departmental sale or annual event. It may 30 optionally be used to permanently dress the main frame and, when no special events are in progress carry a card of conventional design having perhaps no special significance, or bearing for instance, the name of the 35 particular department on the counters of which it is displayed.

40 The device of the present invention is particularly adapted for use in the better class department stores, where it will harmonize with the more elegant fixtures and appurtenances usually found therein. The 45 frames are less readily damaged than the fragile paper cards of my prior application, they are not subject to breakage or soiling by the careless handling of clerks and they are much less apt to tumble out of place and 50 due to the carelessness or stupidity of the

store employees find their way to wrong price card frames.

Other objects of the invention are to provide a display device of extremely simple and practical construction which will be rugged, durable and efficient in use, attractive in appearance and well suited to meet the requirements of economical manufacture and convenient manipulation.

With the above noted and other objects in view, the invention consists in certain novel features of construction and combinations and arrangements of parts which will be more fully hereinafter described and pointed out in the claims.

In the accompanying drawings in which is shown one or more of various possible embodiments of the several features of my invention:

Fig. 1 is a perspective view of a display 70 device embodying the invention, showing the cap frame in place.

Fig. 2 is an enlarged vertical sectional detail through the associated left hand corners of the two frames.

Fig. 3 is a vertical sectional detail on the line 3—3 of Fig. 2.

Fig. 4 is transverse sectional detail on the line 4—4 of Fig. 2.

Fig. 5 is a perspective view of the cap frame 80 itself showing the card which it carries partially removed.

In the drawings the reference numeral 10 designates an open rectangular frame, of light gauge metal or another suitable material, supported in upright position upon a suitable pedestal 11. The lower cross bar and the sides of the frame are internally channeled as at 12 and the top of the frame is provided with a slot 14 through which sign cards 90 may be inserted, the edges of these cards lying in the channels.

The card 13 is of any suitable type, such for instance as that disclosed in the Bloomingdale Patent No. 1,653,033, and in the ordinary course of use two of the sign cards are inserted back to back, the channels and slot being wide enough to readily accommodate them.

The decorative cap frame 15 may also be of 100

generally rectangular shape and of light gauge metal with interior card receiving channels 16 to support a card 17 and with a slot 18 in its top to admit the card into the frame. Card 17 will ordinarily bear either printed or graphic indicia such as 19 relating to a seasonal or special event to be advertised.

The cards and cap frame, however, may be used as more or less permanent decorations 10 for the main frames at all times and the card 17 may carry ornamental or advertising material of any appropriate type, such for instance as a department name serving as a guide to the customer.

15 The cap frame is of no greater (and usually less) thickness than the main frame 10, but is of greater thickness than the width of slot 14, whereby the latter is concealed. Usually the cap frame is of a length less than the 20 length of slot 14 and the ends of the latter are hidden under the flat bottoms of decorative shoulder pieces 25 secured to a projection from the sides of the cap frame. The bottoms of these corner pieces preferably lie 25 flush with and serve as extensions of the bottom of the cap frame. Screws 26 or other suitable, and preferably concealed, securing devices, attach the shoulder pieces to the cap frame.

30 A centering and anti-tilting keel member, usually a downwardly tapering thin metal plate 20 is pendent from the frame 15 and is adapted to enter the slot 14 and lie in concealed position between the cards 13.

35 Many expedients might be resorted for effecting attachment of the keel to the cap frame. I have shown one method of attachment which serves to lock the frame, the shoulder pieces and the keel together in a 40 unitary manner. The upper edge of the keel is formed with extensions or tongues 21 and 22 entering snugly into slots or notches 21^a, 22^a in the under faces of the shoulder pieces and cap frame respectively. One or both sets 45 of tongues may be either friction fitted, or retained by screws 23 or otherwise firmly held in position. This construction is especially effective to prevent twisting or turning of the shoulder pieces about the screws 26 as centers.

50 Inasmuch as the keel fits rather snugly between the two sign cards, this keel or rib engages the rear faces of the cards and it tends to hold these cards and the cap piece 55 against rattling or against falling out of place even though the frame be inverted in carrying, and accomplishes this result without injury to the cards.

60 The particular shape of the cap frame is subject of course to a wide range of variations but it is preferably of a shape which harmonizes with the general shape of the frame 10 and which when in place does not destroy the symmetry of the display. Cap frames having 65 bodies of triangular, semi-circular, rec-

tangular or trapezoidal formation are all quite effective in use.

By tapering the keels no "feeling" about 70 is necessary to properly aline them with the slot and the keels automatically guide the cap pieces into properly centered home position.

When a number of the displays are mounted 75 on a counter or on the display tables in a department store and properly dressed with cap frames bearing appropriate seasonable greetings or seasonable decorations they aid very materially in producing a festive appearance entirely in consonance with the particular occasion which they symbolize or represent. These cap frames add to the decorative 80 appearance of the sign in any event and they permit a store to be very expeditiously and inexpensively dressed up for purpose of an anniversary sale, Christmas sale, etc.

The cap frames being of such simple and 85 inexpensive type may be readily stored away for future use after they have served their purpose and the need for revising, or reprinting all of the price cards and other advertising matter on the counters during a 90 special sale or season is entirely avoided.

It will thus be seen that there is herein described an article in which the several features of this invention are embodied, and which in service attains the various objects 95 of the invention and is well suited to meet the requirements of practical use.

As many changes could be made in the above construction, and many apparently 100 widely different embodiments of this invention could be made without departing from the scope thereof, it is intended that all matter contained in the above description or shown in the accompanying drawings shall 105 be interpreted as illustrative and not in a limiting sense.

Having thus described my invention, what 110 I claim as new and desire to secure by Letters-Patent of the United States of America, is:—

1. A display device including a pedestal and an open frame supported in upright position thereon, said frame including a top piece having a slot therein through which a sign card may be inserted and being internally channelled for the reception of the card, in combination with a removable decorative frame constituting a cap piece resting upon the top of the frame and including a pendant keel adapted to enter the slot, and 115 engaging one face of the card.

2. In a display device a sign and a frame therefor, the frame including a top cross bar having a slot extending therethrough, a decorative cap frame resting upon the upper 120 edge of the first mentioned frame adapted to removably receive a sign card and including a pendant keel lying in the slot, and engaging one face of said sign card.

3. A display device of the character de- 130

scribed including a frame having a slot in its top and a pair of oppositely facing sign cards of no greater width than the slot mounted back to back in the frame, a decorative cap frame of a width greater than the width of the slot resting upon the top of the frame and including a retaining keel to prevent tilting, extending through the slot and lying between the sign cards.

5 4. A display device of the character described including a frame having a slot in its top and a pair of oppositely facing sign cards of no greater width than the slot mounted back to back in the frame, a decorative cap frame of a width greater than the width of the slot resting upon the top of the frame and including an anti-tilting keel extending through the slot and lying between the sign cards, said keel at its point of junction with the body of the cap frame being of a width approximately equal to the length of the slot and tapering toward its free end to provide inclined guiding edges.

10 5. A display device including a main self-supporting frame and a cap frame adapted to be removably mounted thereupon, the main frame having interior channels and a slot in its upper edge to support and admit a sign card and the cap frame including a centering and anti-tilting keel portion entering the slot in the top of the main frame, and engaging the rear face of the sign card.

15 6. A display device including a main self-supporting frame and a cap frame adapted to be removably mounted thereupon, the main frame having interior channels and a slot in its upper edge to support and admit a sign card and the cap frame including a centering and anti-tilting keel portion entering the slot in the top of the main frame and engaging the rear face of the sign card, the cap frame being of greater thickness than the slot whereby it rests upon the main frame at opposite sides of the slot.

20 7. A display device including a main self-supporting frame and a frame adapted to be removably mounted thereupon, the main frame having interior channels and a slot in its upper edge to support and admit a sign card and the cap frame including a centering and anti-tilting keel portion entering the slot in the top of the main frame and engaging the rear face of the sign card, the cap frame being of greater thickness than the slot whereby it rests upon the main frame at opposite sides of the slot, and including shoulder portions beyond the ends of the keel resting on the top of the main frame beyond the ends of the slot whereby the seat is concealed when the cap frame is in place.

25 8. A display device of the character described, including a frame having a slot in its top and a sign card inserted through the slot and mounted in the frame, and a decorative cap frame of a width greater than the

width of the slot resting upon the top of the frame and including a retaining keel to prevent tilting, the keel extending through the slot and engaging one face of the card.

30 9. A display device of the character described, including a frame having a slot in its top, a sign card inserted through the slot and engaged by said frame, a decorative cap frame of width greater than the width of the slot resting on top of the frame, and including an anti-tilting keel extending through the slot and engaging the rear face of the card, said keel at its junction with the cap frame being of a length approximately equal to the length of the slot and tapering at its ends to provide inclined guarding edges.

35 10. A display device comprising a pair of vertically arranged superposed frames, the bottom edge of the upper frame resting upon the upper edge of the lower, which has a slot therein along its upper edge, the upper frame having an external rib secured to its lower edge to project into said slot and snugly engage the rear face of a sign card therein, to hold said card firmly in said lower frame and to keep the upper frame in place.

Signed at New York, in the county of New York and State of New York, this 14th day of May, A. D. 1929.
